NEW YORK.

FRICITION DRAFT-RIGGING.

1,303,276.

Specification of Letters Patent. Patented May 13, 1919.

Application filed April 27, 1918. Serial No. 231,104.

To all whom it may concern:

Be it known that I, JOHN F. O'CONNOR, a citizen of the United States, residing at Chicago, in the county of Cook and State of Illinois, have invented a certain new and useful Improvement in Friction Draft-Rigging, of which the following is a full, clear, concise, and exact description, reference being had to the accompanying drawings, forming a part of this specification.

This invention relates to improvements in friction draft riggings.

One object of my invention is to provide an efficient draft rigging of the friction type for railway cars and wherein the use of the customary stop castings is avoided.

Another object of the invention is to provide a friction draft rigging wherein all of the frictional elements are of simple design and capable of cheap manufacture in the form of castings.

In the drawing forming a part of this specification, Figure 1 is a vertical, longitudinal, sectional view of a portion of a railway draft rigging showing my improvements in connection therewith. Fig. 2 is a horizontal, sectional view of the arrangement shown in Fig. 1 and taken on the line 2-2 thereof. Fig. 3 is a vertical, transverse, sectional view taken substantially on the line 3-3 of Fig. 1. And Figs. 4 and 5 are detail, perspective views of one of the wedge blocks and one of the friction shoes, respectively.

In said drawing, 10-10 denote channel or draft sills of a railway car, the same being preferably reinforced by plates 11-11 riveted to the inner faces thereof, the sills and plates being each provided with three sets of slots 12, 13 and 14 to accommodate keys 15, 16 and 17, respectively. The slots 14 are so designed as to prevent longitudinal movement of the key 17. The slots 12 permit both inward and outward movement of the key 15 and the slots 13 are designed to permit forward movement of the key 16 from normal position, only.

The draw bar 20 by means of the key 15, is operatively associated with the gear or cushioning device proper by a pair of side links 18-18 and a U-shaped strap 19. The connection between the links 18-18 and the draw bar is effected by the key 15, and the links 18 and strap 19 are connected by the key 16.

To form the front stop means of the gear, I employ a vertical cast yoke element 21 having the rear end thereof slotted, as indicated at 22, to receive the key 17 so that said yoke 21 is prevented from both forward and rearward movement. At its forward end, the yoke 21 is formed with a hollow rectangular hood and has upper and lower transversely extending shoulders 23-23 against which normally bears the front combined follower and wedge 24. It will be noted that the side walls 25-25 of the hooded end of the yoke 21 are spaced apart sufficiently to permit the location of the links 18 within the hood so that the latter are brought close to the sides of the draw bar and thus minimize bending strains imposed upon the coupler key 15.

Within the yoke 21, at its rear end, is provided a rear follower 26 having a transverse recess 27 to accommodate the horizontally extending rear connecting sections 28 of the strap 19 so that the follower 26 will be pulled forwardly upon draft movement of the draw bar.

The friction elements include the said follower wedge block 24, a corresponding opposed combined follower and wedge block 29, upper and lower friction shoes 30-30, and a central rectangular friction block 31. Each of the follower wedge blocks 24-29 is provided on its inner side with a pair of oppositely disposed wedge faces 32-32 and the corresponding ends of the friction shoes 30 are made similarly wedge-shaped, as indicated at 33-33. Each of the shoes 30 is provided on its inner face with a horizontally extending friction surface 34, said surfaces 34 cooperating with the upper and lower horizontal friction surfaces 35-35 of the block 31. The block 31 is slotted, as indicated at 36, to receive the key 16, the slot 36 being so designed as to prevent relative movement between the block 31 and key 16. Each of the combined follower wedge blocks 24 and 29 is provided with side plates 37-37 arranged to overlap the adjacent ends of the friction shoes 30-30 and hold the latter against lateral displacement. Said walls 37 will also perform a similar function with respect to the block 31, as clearly appears from an inspection of Fig. 2.

The operation is as follows: Upon inward movement of the draw bar, the follower wedge block 24 will be forced rear-

wardly and due to the resistance of the spring 38 to rearward movement of the follower wedge block 29, there will be a tendency to squeeze or compress the friction 5 shoes 30 toward each other, thus augmenting the friction generated between the shoes 30 and block 31 inasmuch as the latter is prevented against rearward movement by the key 16. It will, of course, be understood 10 that the rear follower 26 is held against rearward movement by the filler section of the yoke 21, the yoke 21 being held stationary by the key 17 as before described. In draft, the follower wedge block 24 will be held stationary by the shoulders 23 of the 15 yoke 21. As the rear follower 26 is moved forwardly through the yoke consisting of the links 18 and strap 19, it is evident that the spring 38 will be compressed and the 20 wedging or squeezing action on the shoes 30 will be correspondingly increased. During the draft movement of the draw bar, it is evident that the key 16 will slide the 25 friction block 31 forwardly, thus generating friction between said block 31 and the shoes 30.

A saddle plate 39 may be employed to assist in supporting the parts, if desired.

With the arrangement above described, 30 it is evident that all the friction elements may be manufactured in the form of comparatively cheap castings and I eliminate the use of the usual comparatively expensive stop castings while at the same time obtaining a friction gear of high capacity. Furthermore, with the arrangement of shoes 30—30 and block 31, I obtain a large frictional wearing area, thus promoting the life 35 of the friction elements.

40 I claim:

1. In a friction draft rigging, the combination with a draw bar, yoke-acting means, and rear and front stop acting means; of a spring; and friction devices, the latter including wedge elements and relatively slid- 45 able friction members, one of said wedge elements remaining stationary under draft and all of the wedge elements being movable in buff.
- 50 2. In a friction draft rigging, the combination with a draw bar and yoke-acting means; of front stop acting means, rear stop-acting means; a spring; and friction devices including a plurality of wedge elements and relatively slid- 55 able friction blocks, said front stop-acting means preventing forward movement of one of the wedge elements; and a key for preventing rearward movement of one of said friction blocks.
- 50 3. In a friction draft rigging, the combination with a draw bar and yoke-acting means; of friction devices including a pair of oppositely arranged wedge elements, a

pair of friction shoes interposed between the wedge elements, and a friction block inter- 65 posed between the shoes and slidable with respect thereto; a spring; and front and rear stop-acting means.

4. In a friction draft rigging, the combination with a draw bar and yoke-acting 70 means; of friction devices including a pair of oppositely arranged wedge elements, a pair of friction shoes interposed between the wedge elements, and a friction block inter- 75 posed between the shoes and slidable with respect thereto; a spring; and front and rear stop-acting means, said front stop-acting means comprising a stationary yoke having shouldered engagement with one of the wedge elements. 80

5. In a friction draft rigging, the combination with shock absorbing means includ- 85 ing a spring and a plurality of friction elements; of a draw bar; and yoke-acting means operatively connecting the draw bar and shock absorbing means, said yoke-acting means including a pair of links, an extension strap, and a key connecting said links and strap, said key extending through one of said friction elements and adapted to prevent 90 said element from rearward movement.

6. In a friction draft rigging, the combination with draft sills and a transversely ex- 95 tending fixed key mounted therein; of a stationary yoke held by said key, said yoke having front stop-acting shoulders; of a plurality of friction elements mounted within said yoke and one of which coöperates with said shoulders; a draw bar; a spring 100 interposed between the rear of said friction elements and the rear of said yoke; and yoke-acting means operatively connected to the draw bar. 105

7. In a friction draft rigging, the combination with draft sills having a stationary key mounted thereon; of a yoke held against movement by said key, said yoke having front upper and lower transversely extending shoulders; a spring mounted within said 110 yoke; friction devices within said yoke and including a pair of oppositely arranged wedge blocks, a pair of friction shoes and a friction block slidably mounted within the shoes, one of said wedge blocks coöperating 115 with said shoulders; a draw bar; and horizontally arranged yoke-acting means connected to the draw bar, said yoke-acting means including a transverse key extending through the friction block and arranged to 120 prevent rearward movement of the latter.

In witness that I claim the foregoing I have hereunto subscribed my name this 12th day of April, 1918.

JOHN F. O'CONNOR.
